UNITED STATES PATENT OFFICE

136,837

DESIGN FOR A GRAIN DISINTEGRATOR OR SIMILAR ARTICLE

Clarence W. Lanter, Du Page County, Ill., assignor to Birtman Electric Company, a corporation of Illinois

Application October 2, 1943, Serial No. 111,255

Term of patent 14 years

To all whom it may concern:

Be it known that I, Clarence W. Lanter, a citizen of the United States, residing in Du Page County, State of Illinois, have invented a new, original, and ornamental Design for a Grain Disintegrator or Similar Article, of which the following is a specification, reference being had to the accompanying drawing, forming a part thereof, in which:

Fig. 1 is a front elevational view of a grain disintegrator or similar article, showing my new design; Fig. 2 is a top plan view thereof; and Fig. 3 is a rear elevational view thereof.

I claim:

The ornamental design for a grain disintegrator or similar article, as shown.

CLARENCE W. LANTER.
